UNITED STATES PATENT OFFICE

CHARLES H. SCHOPBACH, OF AURORA, ILLINOIS, ASSIGNOR TO INTERNATIONAL CORSET COMPANY, OF AURORA, ILLINOIS, A CORPORATION OF ILLINOIS

COMBINATION CORSET AND BRASSIÈRE

Application filed April 13, 1932. Serial No. 604,887.

This invention relates to a combination corset and brassière.

The object of the invention is to produce a well fitting combination garment which is easy to don and is self-adjusting to the figure of the wearer.

Another object is to produce a unitary structure in which the brassière is permanently secured to the corset, in such manner that the back portions of the brassière and corset will be independently self-adjustable to the figure of the wearer.

The garment is attractive in appearance, permits free movement on the part of the wearer without strain on the garment, and properly supports and confines the figure.

In the drawings:

Fig. 1 is a perspective view showing the back of a garment embodying my invention, in position on the figure of a wearer.

Fig. 2 shows the outside of the garment in open, spread out position.

Fig. 3 is an enlarged vertical sectional view taken on the line 3—3 of Fig. 2.

Fig. 4 is a fragmentary view of the outside of the back of a garment embodying a modified form of my invention.

In that embodiment of the invention shown in Figs. 1 to 3, inclusive, the corset is indicated as a whole at 10 and the brassière at 11. The corset is a side opening garment adapted to encircle the body of the wearer from, or slightly above, the waistline to below the hips. The corset comprises a front section which may be formed of any desired number of panels. In the present embodiment it comprises three panels 12, 13, and 14, stitched together, the center panel 13 being made of a plurality of pieces. To one longitudinal side margin of the front panel 12 is secured an elastic panel 15 and the opposite longitudinal side margin of the front panel 14 is provided with fastening means for engaging cooperating fastening means 16 on a similar elastic panel 17 at the side of the garment opposite the panel 15. In the present embodiment the back of the corset between the elastic sections 15 and 17 comprises three non-elastic panels indicated at 18, 19, and 20, stitched to each other along adjacent longitudinal margins, the panels 18 and 20 being also stitched to the elastic sections 15 and 17, respectively. In Fig. 2, the upper margin of the front of the corset is defined by the line 21 and the upper margin of the back and of the elastic sides is defined by the dotted line 22.

The brassière 11 comprises a front member 23, the longitudinal side margins of which are approximately under the arms of the wearer. One of the side margins is provided with fastening means and the other has stitched to it a back member 24. A back member 25 is identical with the member 24 except that it is provided with fastening means 26 for cooperating with the fasteners on the front section 23.

The corset and brassière are secured together, partly by stitching and partly by yielding means. The front 23 is stitched to the top of the corset along the line 21. Each of the back members 24 and 25 has secured to its downwardly extending lower margin 27 toward the side of the corset, a triangular piece of elastic fabric 28, 29, respectively, which is stitched along its side margin to the corset body by lines of stitches 30, 31, respectively. These triangular elastic pieces form a part of each of the back sections of the brassière and overlie the elastic side panels of the corset. Thus the back sections of the brassière are wider from top to bottom than the front 23 of the brassière, and the lower portions of said back sections extend downwardly over the corset. The lower margins of the parts 24, 28 and of the parts 25, 29 extend upwardly from the sides of the garment toward the center back.

The top margins 32 of the back members 24, 25, incline downwardly toward each other as they approach the center of the back, and terminate in elastic strips 34 and 35, respectively. These strips 34 and 35 are preferably made of parallel edged elastic. The width of the strips 34 and 35 and the width of the brassière back sections 24 and 25 may be varied, depending on whether a high, low or medium back is desired. The combined parts 24, 34, 35, and 25 extend across the back of the wearer. Shoulder straps 33 are attached

80

100

to the margins 32 of the back sections and to the top margin of the front 23 of the brassière.

The elastic strips 34 and 35 extend downwardly diagonally toward each other and meet at a vertical line at the center of the back, approximately at or slightly above the waistline, and are stitched together. A piece of fabric 36, preferably in the form of an elongated and relatively narrow medallion, overlies the joined ends of the strips 34 and 35 and is stitched to same by stitches 37. These stitches extend only through the fabric 36 and the joined elastic strips 34 and 35 and 15 not through the back panel 19 of the corset. That portion of the fabric piece 36 which extends below the elastic strips 34 and 35 is firmly secured to the back panel 19 of the corset by lines of stitches 38, and preferably 20 also by a line of stitches 39. The stitches 38 extend through the medallion 36 and corset panel 19, and the stitches 39 extend through the fabric medallion 36, the lower edges of the elastic strips 34 and 35, near their ends, 25 and also through the corset panel 19. By this construction the back of the brassière is independent of the corset back throughout the major portion of its length, but is anchored to the corset by the medallion 36 30 stitched or otherwise fastened to the corset back approximately at the waistline.

The back members of the brassière are preferably not attached to the corset except by means of that part of the medallion 36 35 below the strips 34 and 35, and by the stitching 30 and 31 at the side of the garment where the brassière overlaps the side of the corset. The method of attaching the elastic strips 34 and 35 to the center back of the corset, and 40 the form and arrangement of the elastic strips are such that a gentle downward pull is exerted on the brassière sections when in position on the body of a wearer, resulting in a smooth fit of the brassière top across the 45 busts of the wearer, and yet permitting self-adjustment of the brassière relatively to the back of the corset and freedom of movement of the wearer without straining the shoulder straps or other parts of the garment.

50 In Fig. 4 a modified form of construction is illustrated in which the elastic inserts 28 and 29 have been omitted and the fabric 24 and 25 forming the back sections of the brassière of Figs. 1 to 3, inclusive, is extended downwardly at the sides as indicated at 40 and 41 in Fig. 4. While I prefer to use the elastic inserts 28 and 29, they may be dispensed with as shown in Fig. 4.

The shape of the medallion 36 may be 60 varied without departing from my invention; its function is to anchor the center back of the brassière to the corset in such manner that the elastic strips 34 and 35 will exert a downward pull when under tension, on the 65 figure of a wearer, and without detracting

from the relative independence of the corset and brassière at the back. The fact that the upper parts of the medallion 36 and the strips 34 and 35 are not stitched to the corset panel 19, in the preferred form of my invention, permits slight sidewise movement of the said parts, relatively to a longitudinal median line of the garment. 70

Changes may be made in details of construction without departing from the scope 75 of my invention and I do not intend to be limited to the exact form shown and described, except as set forth in the appended claims. 80

I claim:—

1. A combination garment comprising a corset and a brassière, said brassière comprising a front portion attached to the upper edge of the corset and adapted to cover the body across the busts, end sections secured to the front portion of the brassière and to the sides of the corset and being free from the rear of the corset throughout the greater part of their length, each end section terminating in an elastic strip extending downwardly diagonally to the center back of the corset, the meeting edges of the elastic strips being permanently secured together providing a generally V-shaped elastic member, and means for permanently anchoring said elastic member to the corset back at the center approximately at the waistline, said anchoring means comprising a fabric medallion having its upper portion stitched to and overlying the meeting edges of the elastic member, and its lower portion stitched to and overlying the center back of the corset. 90

2. A combination corset and brassière, the corset comprising a non-elastic front section, elastic side panels and a non-elastic back secured together to encircle the body of the wearer, said corset extending from about the waistline to below the hips, a brassière consisting of a front member and two back members, the front member stitched to the front of the corset, a piece of elastic fabric connecting the lower part of each back member to the side of the corset and overlying said corset elastic panels, an elastic strip secured to each back member of the brassière near the center back and extending diagonally downwardly toward the corset back, and means for anchoring said elastic strips to the corset back without directly securing the said strips to the corset, said anchoring means comprising a fabric medallion having its upper portion stitched to and overlying the meeting edges of the elastic strips, and its lower portion stitched to and overlying the center back of the corset. 100

3. A combination corset and brassière comprising a body encircling garment open at one side and providing connected front and back corset and brassière portions each 110 115 120 125 130

having a free edge, said front portion including a lower corset member and an upper brassière member, said back portion including a lower corset member and two relatively movable back brassière members overlying the upper portions of the back corset member and secured to opposite sides thereof, means permanently securing said back brassière members relative to the central

back portion of the corset comprising a generally V-shaped elastic strip, and an anchoring member stitched at its lower end to the center back of the corset and at its upper end to the central portion of said V-shaped strip, and means detachably securing the free edges of the front and back corset and brassière portions at one side of the garment.

CHARLES H. SCHOPBACH.
